DOOR SPRING BRACKET

Marvin I. Sumner and Lois D. Faulkner,
Dallas, Tex.

Application June 3, 1950, Serial No. 165,906

2 Claims. (Cl. 16—80)

1

This invention relates to improvements in door spring mounting brackets, and more particularly to door spring mounting brackets wherein the spring is held a spaced distance from the door facing during the opening and closing of the door.

Various spring mounting brackets have been proposed heretofore, but these, for the most part, have been complex in construction, difficult to use, or likely to deface the door and the door facing.

The present invention is simple in construction, easy to install and to remove, light in weight and positive in operation.

The primary object of this invention is to provide a door spring bracket that will allow the door upon which it is used to be opened more than ninety degrees without the spring cutting or sawing into the edge of the door.

Another object of this invention is to provide a door spring bracket that will give a hard initial pull of the spring to the door, with the pull decreasing as the door approaches the closing.

Still another object of this invention is to provide a door spring bracket that may be readily reversed so as to be adaptable for use either on a left hand or a right hand opening door.

An embodiment of this invention is illustrated in the accompanying drawing, in which:

Fig. 1 is a plan view of the device embodying the invention installed on a door, with the door and facing thereof shown in section; and with one position of the door shown in dashed outline; and

Fig. 2 is a perspective view of the device embodying the invention detached from the door.

With more detailed reference to the drawing, the numeral 1 designates a door facing on which a bracket 2 is secured by means of screws 3. A rod 4 passes through each of the holes 5 which are provided in bracket 2. Each rod 4 extends outward approximately parallel with the doors D and S, when the doors are in closed position.

An arm 6 is interconnected with each rod 4 by loops 7 and 8, so as to form an acute angle between rod 4 and arm 6 when the rod 4 is approximately in parallel relation with the door D.

A bracket 9 secures the inturned inner ends of each arm 6 to the doors. Each of the brackets 9 is preferably fastened to the respective door D or S by means of screws 11, near the hinged edge of the respective door.

Connected to each of the loops 7 is an eye 13 to which a spring 14 is secured. The springs 14 extend along the doors D and S, and are anchored to the doors by means of eyes 15.

2

It is to be noted, as shown in Fig. 1, that our device constitutes a dual unit for closing two doors that may be in a single opening, such as a door and a screen or a door and a storm door. The mechanism that is attached to the bracket 2 will protrude outward at least the thickness of the door and the two units will not interfere with each other in opening or closing either of the doors.

10

Operation

In the operation of the device, when the door S is opened, as indicated in dashed outline in Fig. 1, the arm 6 will be caused to swing toward the door facing 1 and to protrude outward to increase the tension on the spring 14. At the same time the inner end of the spring 14 will be swung away from the door, until the door swings open beyond ninety degrees of its travel. As the door passes beyond the ninety degree open position, the arm 6 maintains the rod 4 and spring 14 a spaced distance outward from the hinged edge of the door, which enables the door to swing through a substantial arc beyond the ninety degree opening.

25 It is to be noted that when the open door is first released the pull of the spring is quite hard, but as the door closes the tension of the spring becomes less, therefore the door is prevented from closing with a sharp bang.

30 It is to be further noted that at no time during the opening or closing of the door, does the spring come into contact with the door, thus the door cannot be defaced by the spring, as has been true heretofore with door springs used without a bracket.

35 When the device is installed on a pair of doors, that is a door and a screen or storm door, as the case may be, which are in the same opening, the bracket 2 is installed on the common door facing 1. The bracket 2 has rods 4 pivoted thereto, which rods 4 extend outwardly therefrom in substantially parallel relation to the respective doors, and each having the outer end thereof formed into a loop 7, which loops lie in a vertical plane. Each of the doors D and S has an arm 6 hinged thereto by means of a closed U-portion of each arm 6 which is secured to the respective door. The outer end of each arm 6 terminates in a loop 7, which loops are in a horizontal plane. The terminal loop 7 of each rod 4 engages in the terminal loop 7 of the corresponding arm 6 to form a pivot joint. The length of each rod 4 is greater than twice the thickness of the respective door, wherefore, each 45 door may swing outward without the respective

arms 6 coming in contact with the hinged edge thereof.

When each rod 4 swings to its outermost position, the respective loops 7 and 8 will be out of alignment with the respective doors on which the rods 4 and arms 6 are installed, wherefore the springs 14 will thus each be given an extra angular advantage in urging the respective doors D and S to start swinging movement toward their respective closed positions from their respective maximum opened positions.

While the invention has been illustrated and described in one embodiment thereof, it is to be understood that changes may be made in the minor details of construction, and adaptations made to place of use, without departing from the spirit of the invention as claimed.

Having thus clearly shown and described the invention, what is claimed as new and desired to secure by Letters Patent is:

1. In a mechanism for closing a door having a door facing, a bracket secured to the inner face of said door near the hinged edge thereof, an arm extending outward from said bracket at an acute angle to said door when said door is in a closed position, a link, the outer end of which is hingeably connected with the outer end of said arm and extending inwardly, said link being shorter than said arm, a second bracket mounted on said door facing and extending outward therefrom and having a pivot point spaced outward from said door facing a distance greater than the thickness of said door, said link having its inner end pivotally connected to said second bracket at said pivot point so that said link will be substantially parallel with said door when said door is in closed position, and a spring secured substantially at the hinge point of said arm and said link and extending outward therefrom and attached to said door for exerting tension between said door and said second

bracket at an extreme open position of said door for swinging said door inward to closed position.

2. In a dual mechanism for closing a pair of doors which doors have a common facing, each of said doors having a bracket secured to the inner face thereof near its hinged edge, each of said doors having an arm extending outward from the respective brackets, a pair of links the outer end of each being hingeably connected with the outer end of the respective arm, each of said links being shorter than said respective arm, a common bracket mounted on said common door facing and extending outward from said facing and having a pair of pivot points spaced outward from said door facing a distance greater than the thickness of each of the respective doors, each of said pair of links having its inner end pivotally connected to said common bracket at the respective pivot points so said links will be substantially parallel with the respective doors when said respective doors are in closed position, and a spring secured substantially at the hinge points of the respective arms and links and extending outward therefrom and being attached to the respective doors for exerting tension between said doors and said common bracket for swinging said respective doors to closed position.
